DESIGN FOR AN IDENTIFICATION
RECEPTACLE

Henri L. Gaudriot, Rochester, N. Y., assignor to Teale Machine Company, Rochester, N. Y., a firm composed of Richard R. Teale and Henri
L. Gaudriot

Application June 8, 1948, Serial No. 146,824

Term of patent 7 years

(Cl. D17—14)

To all whom it may concern:

Be it known that I, Henri L. Gaudriot, a citizen of the Republic of France, residing at Rochester, in the county of Monroe and State of New York, have invented a new, original, and ornamental Design for an Identification Receptacle, of which the following is a specification, reference being had to the accompanying drawing, forming part thereof.

In the drawing the figure is a perspective view of an identification receptacle, showing my new design.

I claim:

The ornamental design for an identification receptacle, as shown.

HENRI L. GAUDRIOT.
